UNITED STATES PATENT OFFICE

2,435,971
GEM DOP

Jacob Ludel, New York, N. Y., assignor to Diamond Craft of America, Inc., New York, N. Y., a corporation of Delaware

Application October 23, 1944, Serial No. 559,953

4 Claims. (Cl. 51—229)

1. A dop for diamonds, comprising:

This invention relates to dop, more particularly to dop useful in forming girdle facets on gems, and still more particularly for the formation of girdle facets on brilliant-cut type diamonds.

My invention is an improvement of the dop shown in the application of William Ludel, Serial No. 516,337, filed December 31, 1943, and has utility also in connection with my invention for Method for grinding gems and apparatus therefore filed on even date herewith.

It is an object of my invention to provide a gem dop for simplifying the operation of imposing facets upon the girdle of gems; more particularly, faceting of the girdle forming portion of diamonds; and still more particularly, the girdle of brilliant-cut diamonds.

Still more particularly, it is an object of my invention to provide a dop for performing girdle faceting operations on gems, more particularly diamonds, which satisfies the rigid requirements of accurately positioning the girdle or periphery of the diamond at right angles to the staff of the dop for indexing of the girdle in relation to the movable jaws, providing a construction which is capable of assembly quickly, and which involves economy of construction and assembly.

To attain these objects and such further objects as may appear herein or be hereinafter pointed out, I make reference to the accompanying drawing forming a part hereof, in which

Figure 1 is a plan view illustrating my dop, with portions broken away and shown in section;

Figure 2 is a section taken on the line 2—2 of Figure 1;

Figure 3 is a section taken on the line 3—3 of Figure 2;

Figure 4 is a fragmentary side view;

Figure 5 is a section taken on the line 5—5 of Figure 2.

Making reference to the drawings, my dop 10 comprises a block or body portion 11, to the back 12 of which there is screw-threaded one end of a staff or spindle 13 having a shoulder 14. This staff or spindle is designed to rotate within a positioning sleeve (not shown) whose axis is vertical and intersects the operative horizontal surface of a rotary skeif or polishing lap. When so mounted the dop may be turned to present the grain of the diamond at its girdle portion, for best effective polishing operation in forming the girdle facets, in the manner well understood by those skilled in the art, and for other purposes described in said William Ludel application.

The block 11 has a guide surface 15, accurately

formed to facilitate the use of diamonds having a vertical axis to rotate correctly and uniformly when delivered in using a rotary lap, the axis of the diamond being aligned with the girdle facets of the diamond and the diamond being held in the girdle facets by the jaws 16 and 17 placed on opposite sides of the diamond.

2. A dop for diamonds, comprising:

2,435,971

3. A dop for diamonds, comprising:

4. A dop for diamonds, comprising:

2. A dop for diamonds, comprising:

With this construction I provide jaws 16 and 17, each formed with a nose portion 18 and 19, respectively, the nose portions having bearing bores 20 and 21, respectively. These bearing bores are accurately aligned, the bore 20 receiving the spindle 22 of the adapter 23 which engages the diamond crown. The bearing bore 21 receives the indexing spindle of the adapter 25 which engages the pavilion of the diamond.

Each of the adapters 23 and 25 has a shoulder 26 and 27, respectively, to engage the faces 28 and 29 of the jaws 16 and 17, in the manner more particularly described in the William Ludel application aforementioned.

Each of the jaws 16 and 17 has a bearing surface 30 and 31, respectively arranged to engage the guide surface 15 of the bearing block. Each 20 of the jaws 16 and 17 is desirably formed with a horizontal shoulder 32 and 33 respectively, disposed at opposite sides of the neck 34.

With the construction as described, I provide guide plates 35, 36, the upper portions of which 25 are provided with flanges 37 and 38, respectively, arranged to contact the shoulders 32 and 33, respectively, and define a slot 39, through which the necks 34 of the jaws 16 and 17 project.

The plates 35 and 36 are provided with stop 30 flanges 40 and 41, respectively, thereby limiting outward movement of the jaw 17. The jaw 17 carries a horizontal stud 42, the head of which 43 is anchored in the outer face of the jaw 17. The shank 44 of the stud 42 is screw threaded.

35 The jaw 16 is provided with a horizontal bore 45 through which extends a sleeve 46 constituting a portion of an adjusting member 47. The sleeve 46 is internally screw-threaded at 48 for engagement with the threaded shank 44 of the stud 42.

40 The nut 47 is provided with an annular slot

between a radial collar 50 and a shoulder 51.

While the assembly comprising the housing defined by the parts 35 and 36, the jaws 16 and 17, the stud 42, and the adjusting member 47 is held 45 conveniently in one hand, the operator may readily move the jaws 16 and 17 and the adapters 23 and 25 carried by the jaws relatively to a diamond D thus affording easy manipulation of the diamond stock for properly locating it between the adapters, without the necessity for manipulation of the adjusting nut 47.

When one or more diamonds, as when stacking a plurality of such diamonds with filler blocks therebetween as in my companion application, 55 are axially mounted between the adapters 23 and

25, the above assembly may be mounted on the block 11. For this purpose each of the plates 35 and 36 is provided with a pair of parallel guide slots 52, 52 to receive the shanks 53 of the headed screws 54 projecting from opposite sides of the body portion 11.

The body portion or block 11 has at its edge 55 an anchor plate 56, held in position by the screws 57. The plate 56 is formed with fingers 58, 58, defining a slot 59.

With the construction described, the operator aligns the slots 52, 52 over the shanks of the screws 54, adjusting the nut 47 so that the fingers 58 enter the slot 49 until the bearing surfaces 30 and 31 contact the guide surface 15 of the block 11. In this position, the screws 54 are each tightened. Thereupon the adjusting nut 47 may be manipulated for drawing the jaws 16 and 17 to and from each other, either for fixedly clamping the diamond D within the adapters 23 and 25 against rotation, or slightly releasing the jaws 16 and 17 from each other to an extent to permit indexing of the diamond, to expose different portions of the girdle to the skew or polishing surface.

By my construction, I have provided a dop which simplifies the element of manipulation of the jaws in axially aligning the diamond stock between the adapters held by the jaws 16 and 17. Also, considerable economy in labor is effected in the simplification of the machining operations necessary for constructing the various parts.

The ability to draw the jaws 16 and 17 toward each other without screw feeding when the jaws 16 and 17 are disengaged from the block 11 will readily appeal to the skilled diamond worker who has to adjust the diamond stock in the adapters for this purpose.

It will thus be observed that I have provided a dop particularly valuable in connection with accurately axially aligning the diamond, to perform the girdle faceting operation.

It will also be observed that by my construction all clearance tolerance and play between the block 11 and the jaws 16 and 17 may be taken up by the guide plates, as by tensioning of the screws 54 against the guide plates, after securely urging the jaws into firm contact with the guide surface 15. Likewise, manipulation of the screws 57, 57 may be resorted to for adjustment of the anchor plate and the adapter jaws.

In this way a highly accurate arrangement of the dop is secured, notwithstanding the mobility of the parts for assembly, for the adjustments necessary in practicing the girdle faceting operations, and the indexing necessary to rotate the adapters between which the diamond is mounted.

Having thus described my invention and illustrated its use, what I claim as new and desire to secure by Letters Patent is:

1. A dop for use in forming girdle facets on a brilliant cut diamond, said dop comprising a body portion secured to one end of a dop-positioning staff, and a diamond-holding assembly detachably secured to the body portion, said assembly including a housing defining a guideway for a pair of relatively movable work-holding jaws provided with work-engaging elements, a screw-threaded stud fixed at one end to one of said jaws, a rotatable adjusting member having an internally screw-threaded sleeve portion which receives the free end of the stud, the adjusting member passing freely through a bore in the

other jaw whereby the jaws may be slid freely toward and from each other while the assembly is dismounted from the body portion of the dop, thereby facilitating the positioning of a diamond 5 between the work-engaging elements of the jaws, and means for detachably securing the assembly 10 to the body portion of the dop, the body portion and the adjusting member having interengaging parts operative to prevent axial movement 15 of the adjusting member when the assembly is operatively mounted on the body portion of the dop.

2. A dop for use in forming girdle facets on a brilliant cut diamond, said dop comprising a body 15 portion secured to one end of a dop-positioning staff, and a diamond-holding assembly detachably secured to the body portion, said assembly including a housing defining a guideway for a pair of relatively movable work-holding jaws provided with work-engaging elements, a screw-threaded stud fixed at one end to one of said jaws, a rotatable adjusting member having an internally screw-threaded sleeve portion which receives the free end of the stud, the adjusting 20 member passing freely through a bore in the other jaw whereby the jaws may be slid freely toward and from each other while the assembly is dismounted from the body portion of the dop, thereby facilitating the positioning of a diamond 25 between the work-engaging elements of the jaws, and means operative, when the assembly is mounted on the body portion of the dop, to clamp the jaws against relative movement.

3. A dop for use in forming girdle facets on a 30 brilliant cut diamond, said dop comprising a body portion secured to one end of a dop-positioning staff, and a diamond-holding assembly detachably secured to the body portion, said assembly including a housing defining a guideway for a

35 pair of relatively movable work-holding jaws provided with work-engaging elements, a screw-threaded stud fixed at one end to one of said jaws, a rotatable adjusting member having an internally screw-threaded sleeve portion which receives the free end of the stud, the adjusting 40 member passing freely through a bore in the other jaw whereby the jaws may be slid freely toward and from each other while the assembly is dismounted from the body portion of the dop, thereby 45 facilitating the positioning of a diamond between the work-engaging elements of the jaws, and means operative, after the assembly has been secured to the body portion of the dop, to clamp 50 and fix the adjusting member.

4. A dop for use in a machine for faceting the girdle of a diamond whose crown and pavilion facets have already been formed, the dop having a staff designed to turn about an axis radially spaced from but parallel to the axis of a rotating 55 lap whereby the grain of the diamond may be arranged most advantageously for cutting with respect to the operative surface of the lap, characterized in that the dop comprises a rigid block having a rectilinear guide surface perpendicular 60 to the axis of rotation of the dop, an assembly which is removable as a unit from the block and which comprises a pair of jaws which are freely movable toward and from each other when the assembly is separated from the block, each jaw having a support for a rotatable part carrying a 65 diamond-engaging element, the axes of said supports being aligned and the diamond-engaging elements being opposed and adapted, by approach of the jaws, to grip a diamond between 70 them, the assembly also including a housing for

the jaws, the housing and block having cooperative parts whereby the housing may be fixedly secured to the block, and means operative, when the assembly is secured to the block, for applying force thereby to adjust the jaws relatively toward each other and to hold them in adjusted position.

JACOB LUDEL.
